Specification for Design.

Patented July 20, 1920.

Application filed April 9, 1920. Serial No. 372,670. Term of patent 3½ years.

To all whom it may concern:

Be it known that I, HERMAN H. WOLTER, a citizen of the United States, residing at Meriden, county of New Haven, and State of Connecticut, have invented a new, original, and ornamental Design for a Support, of which the following is a specification, reference being had to the accompanying drawing, forming a part thereof.

In said drawing:

Figure 1 is a side view of an ornamental support embodying the design of my invention.

Fig. 2 is a plan view of the same.

I claim—

The ornamental design for a support substantially as shown.

HERMAN H. WOLTER.
